US00D981334S

(12) **United States Design Patent** (10) Patent No.: **US D981,334 S**
Underhill et al. (45) Date of Patent: **** Mar. 21, 2023**

(54) **JUMP STARTER**

- (71) Applicant: **THE NOCO COMPANY**, Glenwillow, OH (US)
- (72) Inventors: **Derek Michael Underhill**, Tempe, AZ (US); **Jonathan Lewis Nook**, Gates Mills, OH (US)
- (73) Assignee: **The Noco Company**, Glenwillow, OH (US)

(**) Term: **15 Years**(21) Appl. No.: **29/759,038**(22) Filed: **Nov. 19, 2020**(51) LOC (14) Cl. **13-02**

(52) U.S. Cl.

USPC ..... **D13/107**(58) **Field of Classification Search**

Primary Examiner — Kendra Leslie Hamilton*Assistant Examiner* — Amanda Christensen(74) *Attorney, Agent, or Firm* — Jones Day(57) **CLAIM**

The ornamental design for a jump starter, as shown and described.

DESCRIPTION

FIG. 1 is a top, front, left side perspective view of a jump starter, showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines in the drawings depict portions of the jump starter that form no part of the claimed design.
